(57) **CLAIM**

The ornamental design for a pipette tip, as shown and described.

DESCRIPTION

FIG. 1 is a perspective view of a pipette tip showing our new design;

FIG. 2 is a top view of the pipette tip;

FIG. 3 is a bottom view of the pipette tip; and,

FIG. 4 is a side view of the pipette tip.

The broken lines in the drawings depict portions of the pipette tip that form no part of the claimed design.
